UNITED STATES PATENT OFFICE.

FRANK ALEXE, OF LONDON, ENGLAND.

APPARATUS FOR FORMING CASKS, BARRELS, OR OTHER SIMILAR RECEPTACLES MADE WITH STAVES.

SPECIFICATION forming part of Letters Patent No. 787,349, dated April 18, 1905.

Application filed May 9, 1904. Serial No. 207,063.

To all whom it may concern:

Be it known that I, FRANK ALEXE, director of public companies, a citizen of the United States of America, residing at 123 Cannon street, in the city of London, England, have invented certain new and useful Apparatus for Forming Casks, Barrels, or other Similar Receptacles Made with Staves, of which the following is a specification.

10 This invention relates to an apparatus for forming casks, barrels, and other similar receptacles which are capable of being taken to pieces and are made of staves joined together by means of wires or metal hoops.

15 In the accompanying drawings, Figure 1 is a perspective view of the staves of a cask joined together in the manner indicated. Fig. 2 is a perspective view of the cask-forming apparatus shown open, as at the moment when 20 the formation of a barrel is begun. Fig. 3 is a plan of same, represented as encircling a completely-formed barrel. Fig. 4 is a perspective view of a finished barrel ready for filling.

25 The same parts where they occur are correspondingly lettered in all the figures.

The apparatus consists of a kind of cage made in two parts hinged or otherwise jointed together and of dimensions suited to the barrel to be formed. Each of these parts is composed of a series of similar hoop-halves *a* and *b*, fixed, respectively, by their ends to uprights *d*, *e* and *f*, *g*. The uprights *d* and *e* for the hoop-halves *a* are fixed on a base *h*, 35 while those for the hoop-halves *b* are movable, one of them—viz., *f*—being jointed with hinges *c* to the corresponding upright half *d*, and the other—viz., *g*—being supported on the base *h* by means of a roller or wheel *i*, attached to its lower extremity.

The movable part of the cage is secured and locked to the fixed part thereof by means of a screw *j*, pivotally mounted on the upright *e* and which can be brought round into the slot 45 *k* in the lug *l*, fixed on the upright *g*. This screw *j* is provided with a nut *l*, fitted with a handle *m* for the purpose of bringing the hoop-halves *b* close to the halves *a*.

The screw *j* may be replaced by a cam-lever,

clamping-tool, or any other device capable of serving the same purpose.

The action is as follows: The staves *r* intended to form a cask or barrel are first arranged together somewhat in the form of laths or slats by means of wires *n* passing through staples *o*, fixed on each stave. The apparatus having been opened, the collection of connected staves is introduced vertically therein, care being taken to arch the central part so as to fit the staves in the fixed hoop-halves *a*, as shown in Fig. 2. A cask-bottom or end piece *p* is then placed in the upper rabbet formed in the staves *r*, and the hoop-halves *b* are brought near to the halves *a*, the two end staves being previously introduced 65 into the hoop-halves *b*. The screw *j* is brought round into the slot *k* in the lug *l*, care being taken to loosen the nut *l* sufficiently to allow of its being held between the catches formed by the lug. Then by operating the handle 70 *m* the hoops *b* are vigorously pulled, whereby the absolute juxtaposition of the staves and the making of them very tight against the end piece *p* are insured. During this operation the free ends of the wires *n* have not 75 been fixed. This is effected by putting tension on the wires *n* and then twisting the ends over one on the other.

Any suitable tool or tools may be used for putting the necessary tension on the wire 80 hoops and twisting or otherwise securing the ends of the same together, and when the wires have been put under the desired tension and the ends twisted or otherwise secured together the fastening-staples *o* are used to fasten down 85 the ends of the hoops.

The lowermost wire *n* is left unfastened. The hoop-halves *b* are then loosened by loosening the nut *l*, and the formed cask is released from the cage and stood bottom end 90 down, as shown in Fig. 4. To close the cask after filling, a top or end piece *p'* only is required. The introduction of this top piece *p'* is facilitated by the flexibility of the ends of the staves which have not yet been joined 95 together by the top end wire *n*. This last-mentioned operation is not carried out until the barrel has been filled and ready for de-

spatch, after which it is secured in the same manner as the other wire hoops *n*.

After being used the barrel may be taken to pieces by simply removing the staples *v*, which hold the ends of the wires *n*, and unhooking said ends. The staves resume their original flat lath-like form, and several may then be placed one on the other, so as to occupy as little space as possible.

10 Having fully described my invention, what I claim, and desire to secure by Letters Patent, is—

In an apparatus of the character described, the combination with a base, of a vertically-
15 arranged semicylindrical section fixedly se-

cured at one end to the base, a vertically-arranged semicylindrical section having a pivotal connection at one of its vertical edges with a vertical edge of the fixed section, a roller mounted at the free end of the pivoted section and adapted to run upon the base, and means for drawing the movable section toward and locking it to the fixed section.

In testimony whereof I have hereunto set my hand, in presence of two subscribing witnesses, this 20th day of April, 1904.

FRANK ALEXE.
